(57) **CLAIM**

The ornamental design for a baby car camera, as shown and described.

DESCRIPTION

FIG. 1 is a front, left and top perspective view of a baby car camera, showing my new design;

FIG. 2 is a rear, right and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.

The broken lines shown in the drawings illustrate portions of the baby car camera that form no part of the claimed design.
